UNITED STATES PATENT OFFICE.

JAMES S. BALL, OF ST. LOUIS, MISSOURI.

VALIDATING TICKET PUNCH.

Application filed November 3, 1923. Serial No. 672,467.

To all whom it may concern:

Be it known that JAMES S. BALL, a citizen of the United States of America, residing at 457 Eichelberger Street, in the city of 5 St. Louis and State of Missouri, has invented certain new and useful Improvements in Validating Ticket Punches, of which the following is a specification.

The object of my invention is to devise 10 a validating ticket punch to be used primarily by railroad conductors and auditors. In checking over the collection of tickets by railroad conductors by auditors, it becomes highly advantageous in order to prevent 15 misappropriation of tickets that the tickets when punched shall not only be perforated in the conventional way, but shall have printed thereon the date, etc. My ticket punch perforates the ticket and prints the 20 name on the ticket simultaneously.

A further object is to devise a ticket 25 punch that will be simple in construction, easily operated, made of few and simple parts that lend themselves readily to multiple production and that will be small in size.

With these and other objects in view, my 30 invention has relation to certain novel features of construction and arrangement of parts as will be hereinafter more fully described, pointed out in the claim and illustrated in the drawings, in which—

Fig. 1 is a front elevation of my device. The solid line indicates my ticket punch 35 in an open or non-printing position and the dash line indicates my ticket punch in a closed or printing position.

Fig. 2 is a plan view of my device, and

Fig. 3 is an end elevation of my device. 40 I have incorporated in my device as many of the features of the standard punch as is compatible with my purpose and structure.

Numerical 4 designates the upper jaw having the handle 5 formed integral therewith 45 and numerical 6 designates the lower jaw having the handle 7 formed integral therewith. The upper jaw 4 and the lower jaw 6 are pivotally secured together by the jaw pivot 8. Near the end of the lower jaw 6 50 is formed the die 9 which may be of any shape in order to make perforations of different contours. Numerical 10 designates a resilient pad which is secured to the lower jaw 6 as clearly shown in Fig. 1. The purpose of this pad as will be discerned later, 55 is to facilitate the printing on the ticket so

as not to have the type letters impinge through the card directly on metal, but on a resilient material. By means of the type bolt 11, which passes through a hole near the external end of the upper jaw 4, the type disks 12 are secured. I have illustrated four such type disks. The type bolt 11 has the head 13 at one end and the bolt 14 in threaded engagement therewith at the other end. 60 Two of the type disks 12 are positioned on each side of the upper jaw 4. On the periphery of the type disks 12 are formed numeral type from zero to nine both inclusive. Between each of the numerals on each 65 type disk is formed a fragmental radial slot 15. The type disks 12 are positioned in rotational engagement on the type bolt 11 so that each type disk may be separately rotated on the type bolt. In order to sheathe 70 the type on the type disks 12 against dirt and mechanical abuse, two sheaths 16 are secured to the upper jaw 4, one being fastened on each side of the upper jaw 4. The sheaths are secured to the upper jaw 4 by 75 means of a small bolt 17. The sheaths are arcuated so as to extend partially around the upper and exposed peripheries of the type disks 12. The loose ends of the sheaths 16 are bent radially inwardly so as to engage 80 the slots 15 when in normal position. Therefore, by means of the sheaths 16 the type disks 12 are held in any selective position. Near the external end of the upper 85 jaw 4 is integrally formed the conventional punch 18. A stripper plate 19 having a perforation in it of the same shape substantially as the punch 18 is secured at right angles to the stripper pin 20. A coil spring 21 is made to envelop the stripper pin 20, 90 the upper end of the stripper pin passing through a hole 22 in the upper jaw 4. The head on the stripper pin prevents the pin from passing through or separating from the upper jaw 4. 95

In order to provide an inking pad for the type disks 12, I have provided the inking pad 23 which is secured to the end of the bifurcated arm 24, one portion of which passes on each side of the upper jaw 4 and 100 the lower jaw 6. The opposite end of the bifurcated arm 24 is rotatively secured by the rivet 25 to the links 26. The ends of the links 26 are rotatively secured, one to the handle 7 and the other to the handle 5 105 as clearly shown in Fig. 1. An eye 27 is formed integral with the handle 7. An

eye 28 is likewise formed in the bifurcated arm 24. A coil spring 29 has its one end secured in the eye 27 and the other end secured in the eye 28. The spring 29 per-
5 forms the dual function of holding my de-
vice normally in an open or non-printing
position and likewise holding the bifurcated
arm 24 and hence the inking pad 23 against
the type disks 12 at all times. It will be
10 seen that when my punch is brought from
an open to a closed, i. e. to say, from a non-
printing to a printing position that the pad
10 is moved rearwardly out of the pad of
the type disks 12 in their approach to the
15 pad 10. This permits the punch 18 to en-
ter the die 9 in order to make the desired
perforation and also permits the type on
the type disks to make an impression on the
ticket which is being operated upon. When
20 the punch is released to a non-printing po-
sition, the inking pad 23 is automatically
forced forward to a contact with the type
disks 12. By having the month of the year
indicated by a number and the day of the

month by another number or numbers, the 25
impression made on the ticket may be the
perforation and the date. With my punch
the ticket may be easily taken hold of and
will remain in position during the printing
and punching operation without being held. 30

What I claim and mean to secure by Let-
ters Patent is—

A punch comprising an upper and lower
jaw pivotally secured together, printing
means secured to one of said jaws, a bifur-
cated arm enveloping said jaws on two op-
posite sides, an inking pad secured near one
extremity of said arm, the other end ro-
tatively secured to links at its other end,
said links secured at their loose ends to the
extensions of said jaws, a spring secured to
one of said jaws at one end and to said bi-
furcated arm at the other, in order to nor-
mally hold said jaws in an open position. 40

In testimony whereof I affix my signa-
ture. 45

JAMES S. BALL.
